UNITED STATES PATENT OFFICE.

JOHN W. WILLSON, OF GRANITE CITY, ILLINOIS.

STREET-INDICATOR.

No. 836,166.

Specification of Letters Patent.

Patented Nov. 20, 1906.

Application filed February 7, 1906. Serial No. 299,980.

To all whom it may concern:

Be it known that I, JOHN W. WILLSON, a citizen of the United States, residing at Granite City, in the county of Madison and State of Illinois, have invented a new and useful Street-Indicator, of which the following is a specification.

This invention relates to devices for indicating the streets or stations of street or rail-way lines, and has for its object to improve and simplify the construction and increase the efficiency of devices of this character.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that various changes in the form, proportions, and minor details of construction may be resorted to without departing from the principle or sacrificing any of the advantages of this invention within the scope of the appended claims.

In the drawings, Figure 1 is a side elevation, partly in section, of the improved device. Fig. 2 is a front elevation with the front of the casing removed and the casing partly in section. Fig. 3 is a detail view, on a reduced scale, of a portion of a street-car, trolley-wire, and trolley mechanism with the improved devices applied thereto. Fig. 4 is an enlarged detail of the trolley-head and a portion of the trolley-wire with the circuit-closing mechanism attached thereto. Fig. 5 is an enlarged sectional detail of a portion of the combined shipper-lever and circuit-closer.

The improved device may be applied to any of the various forms of electrically-operated cars, but for the purpose of illustration is shown applied to a car operated from an overhead trolley-line of the usual construction, the car-body being represented at 10, the trolley-pole at 11, the trolley-head at 12, the trolley-wheel at 13, and the trolley conductor-wire at 14, these parts being of the usual construction, except that the trolley-wire is provided with projections 9 adjacent to the street-crossings, stations, or other stop-

ping-places, the object to be hereinafter explained.

The indicating devices are inclosed in a casing 15, arranged at a convenient point within the car, preferably at one end, as shown in Fig. 3, and within view of the passengers.

The improved indicating mechanism consists of two shafts 16 17, spaced apart and mounted for rotation in the casing and carrying drums 18 19, with flanges 20 21 at the ends.

A belt 22, of suitable material, preferably canvas or the like, is connected at the ends to the drums 18 19 and adapted to be wound from one to the other, the belt to contain the names of the streets or stations in continuous order. The belt 22 is arranged to run over guide-rollers 23 24, the latter disposed near one side of the casing, in which an aperture 25 is formed and covered with a transparent body 26, such as glass or the like. The glass-covered aperture provides means for displaying the street or station names in successive order as the belt is operated.

Presser-rollers 27 28 are arranged to bear upon the belt upon the drums and are retained yieldably in contact therewith by springs 29 30 to prevent the belt running too freely from the drums.

Running loosely upon the shafts 16 17 are ratchet-wheels 31 32, the ratchet-wheel 32 having a clutch member 34.

Slidably disposed upon the shaft 16 and caused to rotate therewith by a feather 35 is a clutch member 36, adapted to be engaged with and disengaged from the clutch member 33 on the ratchet-wheel 31, while a similar clutch member 37 is disposed slidably upon the shaft 17 and caused to rotate with the shaft by a feather 38 and adapted to be engaged with and disengaged from the clutch member 34 on the ratchet-wheel 32.

Mounted to oscillate upon a shaft 39 is a shipper-lever 40, having forked ends 41 42 engaging shipper-channels in the hubs of the clutch members 36 37. By this arrangement when the lever 40 is set in a vertical position the clutch members 36 37 will both be disconnected from their respective clutch members 33 34 and the drums likewise disconnected from the ratchet-wheels. Then if the shipper-lever be moved in one direction the clutch members 33 and 36 will be coupled and the clutch members 34 and 37 uncoupled, and when the shipper-lever is reversed in po-

sition the clutch members 34 37 will be coupled and the clutch members 33 36 uncoupled.

Pivoted at 43 to the casing 15 is an arm 44 and coupled at its free end at 45 to another arm 46, swinging upon the shaft 16 and with a pawl 47, carried by the pivot 45 and engaging the ratchet-wheel 31 and held yieldably in engagement therewith by a spring 48.

10 The ratchet-wheel 31 has a stop-pawl 49 to prevent retrograde movement thereof, and the arm 44 has a spring 50 operating to hold the arm 44 and its pawl yieldably in elevated position.

15 Pivoted at 51 to the casing 15 is an arm 52 and coupled at its free end at 53 to another arm 54, swinging upon the shaft 17 and with a pawl 55 carried by the pivot 53 and engaging the ratchet-wheel 32 and held yieldably 20 in engagement therewith by a spring 56.

The ratchet-wheel 32 has a stop-pawl 57 to prevent retrograde movement thereof, and the arm 52 has a spring 58 operating to hold the arm 54 and its pawl in depressed position, 25 as in Fig. 1.

Extending from the casing 15 is a bracket 59, carrying two electromagnets 60 61, preferably of the solenoid form, with the movable cores 62 63 connected, respectively, at 64 65 30 to the arms 44 52, so that when the magnets are energized the arms and their attachments will be actuated, as hereinafter explained.

Attached to the bracket 59 are spaced contact-plates 66 67, insulated from each other 35 by a block 68 of rubber, vulcanite, or the like and connected by conductor-wires 70 69, respectively, to the magnets 61 60, the latter in turn connected, as by wires 71 72, to the source of electric energy.

40 Extending from the shipper-lever 40 is a handle 73, having a contact-arm 74 extending therefrom between the contacts 66 67 and adapted to alternately engage the same as the handle is operated or to be held out of 45 contact with both when the handle is in central position. The arm 74 is insulated, as at 80, from the handle 73 and connected by wire 75 to a contact 76 on the trolley-pole 11.

Pivoted at 77 to the trolley-head 12 is a 50 lever-arm 78, one end extending beneath the contact 76 and the other end extending to a point near the trolley-wire 14 and held yieldably in position by a spring 79.

The free upper end of the arm 78 is held by 55 the trolley-wheel 13 normally out of contact with the trolley-wire 14 while running beneath the unobstructed portion of the same; but when the arm 78 engages one of the depending contacts 9 the arm is depressed 60 thereby and caused to contrast with the member 76 and close the circuit leading through the magnets 60 or 61, as the case may be, the operation to be hereinafter explained.

65 The belt 22, being provided with the names

of the streets, stations, or other stopping-places in the order of their occurrence, is wound upon one of the drums 18 or 19, as the case may be, with the name of the first street or station toward which the car is moving 70 opposite the glass-covered aperture 25.

For the purpose of illustration it is assumed that the belt is wound upon the drum 19 and unwound from the drum 18 and that the car is to proceed in the direction which 75 will require the streets or stations to be displayed by winding the belt upon the drum 18.

The handle 73 is moved to connect the arm 74 with the contact 67, thus "cutting in" the magnet 60 and "cutting out" the magnet 61, this movement of the handle also operating the shipper-lever 40 and closing the clutch 33 36 and opening the clutch 34 37 and releasing the drum 19. Then as the car proceeds no effect is produced until the contact-arm 78 reaches the first depending member 9, when the arm 78 will be depressed thereby and close a circuit through the arm 78, contact 76, wire 75, arm 74, contact 67, wire 69, and magnet 60, energizing the latter and 80 causing the core 62 to depress the lever 44 and cause its pawl to rotate the drum 18 a distance equal to one of the teeth of the ratchet-wheel 31, which correspondingly moves the belt 22 sufficiently to expose the 85 next street or station.

As soon as the arm 78 passes the projection 9 the spring 79 restores the arm to its former position and again breaks the circuit and permits the spring 50 to restore the arm 44 and its attachments to their former position ready for the next action. Thus the device will be automatically operated and display the street or station names in the required order. 90

When the end of the route is reached, the lever 73 is reversed, which also reverses the clutches and the contact-arm 74, the current then being conducted through the magnet 61 and operating the lever-arm 52 and its connections and rotating the drum 19 and winding the belt in the reverse order. 100

The device is simple in construction and can be readily adapted to the different systems of electric railways or trainways, as will 115 be obvious.

The projections 9 are so slight that they do not interfere with the trolley-wheels 13, which pass them without disturbance.

Having thus described the invention, what 120 is claimed is—

1. In an indicator of the class described, two drums spaced apart, a belt connected to said drums and adapted to be wound alternately from one to the other, a clutch associated with each of said drums, a ratchet-wheel associated with each of said clutches, an arm swinging upon each of said ratchet-wheels and with a pawl swinging from each 125 of said arms and respectively engaging said 130

ratchets, an electromagnet associated with each of said arms and adapted to operate the same when energized, a lever swinging between said clutches and adapted to alternately connect and disconnect the same and provided with a lateral arm, a contact member connected to said lateral arm, spaced contacts electrically connected respectively with said magnets and with which the contact connected to said lateral arm is adapted to be alternately engaged as the lever is operated, and a circuit-closing means associated with said lateral-arm contact.

2. In an indicator of the class described, an inclosing casing, two spaced shafts rotative in said casing and provided with drums carrying an indicator-belt, a clutch member loose upon each of said shafts, an opposing clutch member slideable upon each of said shafts and rotative therewith, a ratchet-wheel attached to each of said loosely-disposed clutch members, an arm swinging upon each of said shafts, arms swinging from said casing and movably coupled at their free ends to the free ends of the arms swinging

from said shafts, pawls swinging from the joints between said arms and adapted to engage said ratchet-wheels, electromagnets having armatures movably associated therewith and coupled to the arms swinging from the casing, spaced contacts in electrical connection respectively with said electromagnets, a lever swinging between said slideable clutch members and movably coupled to the same and provided with a lateral arm, a contact member carried by said lateral arm and in electrical connection with the source of electric energy and adapted to be alternately engaged with said spaced contacts and thereby alternately energize said magnets, and a circuit - closing means associated with the contact connected to said lateral arm.

In testimony that I claim the foregoing as my own I have hereto affixed my signature in the presence of two witnesses.

JOHN W. WILLSON.
